UNITED STATES PATENT OFFICE.

ERNEST REIN, OF MILWAUKEE, WISCONSIN.

DEVICE FOR GRINDING AND GROOVING MILL-ROLLERS.

SPECIFICATION forming part of Letters Patent No. 289,556, dated December 4, 1883.

Application filed December 20, 1881. (No model.)

To all whom it may concern:

Be it known that I, ERNEST REIN, of Milwaukee, in the county of Milwaukee, and in the State of Wisconsin, have invented certain new and useful Improvements in Devices for Grinding and Corrugating Mill-Rollers; and I do hereby declare that the following is a full, clear, and exact description thereof.

This invention is designed as an improvement on a machine consisting, essentially, of a lathe-bed with bearings for arbors, a slide-rest carrying cutters, a feed-screw for actuating the slide-rest, and actuating and shifting mechanism for cutting grooves in mill-rollers; and the main object of my improvements is to improve the efficiency of this machine.

My improvements consist in the novel construction and combination of parts, as will be hereinafter more fully set forth.

In the drawings, Figure 1, Sheet 1, is a side view of my invention with the parts in position for grinding a mill-roller. Fig. 2, Sheet 1, is a plan with the grooving mechanism adjusted for action. Fig. 3, Sheet 2, is an elevation of the driving end of my machine; Fig. 4, Sheet 2, a like view of the feeding end. Figs. 5 and 6, Sheet 3, are details of the feeding mechanism, partly in elevation and partly in section. Fig. 7 is a plan view of the tool-carriage reversing mechanism and clutch. Fig. 8 is an end view of the shifting mechanism. Fig. 9 is a perspective view of the tool-carriage. Fig. 10 is a plan view of the same and adjuncts. Fig. 11 is an end view thereof, and Fig. 12 is a sectional view of the bevel-gear operating the shifting mechanism of the clutch.

A is the frame of my machine, and A' is a carriage sliding on ways fixed to one side of the frame. Through a screw-threaded aperture in the carriage A', or a nut depending from it, I extend a lead-screw, M, the shaft M' of which has its bearings in the ends of the carriage A'. Just outside of its bearing, on the front or power end of the shaft M', a bevel-wheel, I, is keyed to it. This bevel-wheel I is dish-shaped, and has a central hub, i, on which is keyed a miter-wheel, K. On its opposite end, the shaft of the lead-screw M is continued through the frame A, and carries a bevel-wheel, N, and worm O'. The bevel-

wheel N gears with another bevel-wheel, N', on the other end of the shaft of which is a cog-wheel, d, geared with a cog-wheel, d', on shaft U by an idler, d''. On the end of shaft U, opposite the cog-wheel d', is a worm, U', that gears with a segment, T, (see Fig. 4,) for a purpose hereinafter to be explained. The worm O' on the shaft M gears with a wheel, O, that carries a cam, P, the lower end of which is designed to act upon an arm, q, of a lever, Q, as seen in Figs. 2 and 6. The arms of lever Q spring from a sleeve, q', that is keyed on one end of a shaft, s, on the opposite end of which is a forked arm, R, that engages with a sleeve, Z', on a hollow shaft, Z, within which is a rod, p, connected to said sleeve, so that the weight q' on arm q' of lever Q will always have a tendency to throw the rod p in the direction of the arrow, lever Q being limited in its action by an adjusting-screw, q'', that, passing through its arm q', rests upon the bed of the frame. Slots in shaft Z (see Figs. 1 and 5) permit the proper play of the sleeve Z'. The segment T has a flange, T', and a hub, which fits upon the hub of a worm-wheel, V, that is keyed to hollow shaft Z. The flange T' of segment T has bearings t for the upright shaft of a worm, w. The shaft of worm w is reduced near its top, to receive loosely the hub of a small segment, b, and above this hub is keyed a ratchet-wheel, c. On its top the flange T' is provided with lugs, to which is bolted the bearing c' of a vertical shaft, that carries a segment, b', on its upper end, and a small spur-wheel, a', on its lower end. The segment b' meshes with segment b, (see Figs. 2, 5, and 6,) and a pawl, c'', engages with the teeth on ratchet-wheel c, so that any outward motion of the rod p will be communicated by rings a thereon to gear or spur a' and segment b, the pawl c'' of which will jig the ratchet c, thus turning the shaft of worm w, which worm, as it meshes with the worm-wheel on shaft Z, will rotate it slightly.

A pulley, C, fixed to a shaft, L, communicates the power by which my machine is driven. Near its pulley end (see Figs. 2 and 3) this shaft L turns in a housing, L', and is provided with a worm, D. It also carries loosely a bevel-wheel, I', the hub of which is serrated to engage with one of the serrated

- ends of a sleeve, H, that is keyed to shaft L, in such a manner as to have longitudinal play. The shaft L passes through another sleeve, L², and on this sleeve are adjustably secured by 5 set-screws miter-wheel K' and bevel-wheel I'. From the lower portion of housing L' (see Figs. 3 and 8) I extend a bar, l, and to the outer end of this I pivot a bell-crank lever, l', the end of one arm of which is forked and engages 10 with the sleeve H, and the other I pivot to a spring-rod, r, that passes through a tubular arm, r', on the end of a short rod, r'', that works in hanger r'''. Bevel-pinion o o' connect rod r'' with a rock-shaft, n, the arm n' of 15 which is pivoted to a rod, m, that extends along in front of the ways A'', and has two adjustable collars, 1 and 2, in position to receive the impact of a projection, m', on the carriage that carries the cutting-tool.
- 20 So far I have described my machine with reference to its action in grooving chilled rollers, and this it does as follows: In Fig. 2 the carriage is shown as having traveled nearly half the distance along the face of a roller to make a groove. The shaft L is being turned by the pulley C, and bevel-wheel I' is in gear with the bevel-wheel I, which turns the lead-screw and slowly revolves it to draw the carriage, which, after it has reached the end of 25 the roller, continues to advance until the projection m' or the lower edge of its face strikes the projection 2 on rod m. This moves the arm n' of the rock-shaft n, and causes the bevel-wheel o to revolve its companion o', and this causes the shaft r'' to revolve far enough to turn its arm and shift the clutch H to reverse the motion of the carriage A'. How this is done I will explain by reference to Figs. 1, 3, 30 7, and 10. In these figures the clutch or sleeve 35 H is shown in gear with bevel-wheel I', so that the larger bevel-wheel I is being revolved by the small bevel-wheel I', and the lead-screw is slowly drawing the carriage and its tool along the face of the roller. The tubular arm r' on shaft r'' and the spring-rod are horizontal, and the lower arm of lever l' is pointing downward. Now, the carriage A' is being drawn slowly in the direction of the arrow by the operation of small bevel-wheel I' upon 40 large bevel-wheel I. After the tool has cleared the roller a projection, m', on the carriage will strike the projection 2 on rod m, and this will move the arm of rock-shaft n, and through bevel-gearing o o' give just enough rotation to 45 rod r'' to cause it to overcome the tension of the spring on rod r, and raise it to such an angle as to throw the lower arm of lever l' above the center, when the expansive force of the spring will drive said arm upward, and thus throw 50 the clutch or sleeve H into gear with the sleeve L², and hold it there. This occurs when the carriage A' has reached its limit of travel toward the shaft L, and is ready to return, and up to this point the sleeve or clutch 55 H has of course been intermeshed with the hub of bevel-wheel I'. Now, at the moment that projection m' on the carriage strikes the

projection 2 of the rod m, arm X of the rock-shaft x' strikes against lug 3, fixed to the frame A, and is thrown back far enough to cause 70 the arm x'' and rod x³ to act upon a lever which projects from the circular tool-holder, and turn it back, so as to withdraw the tool from contact with the roller during the return of the carriage to the place of starting. At the 75 moment of contact of the arm X with lug 3, the projection m', as heretofore stated, strikes the projection 2 of the rod m, and drives forward the arm n', turning the bevel-gear o and o', which resultantly shifts the clutch H, and reverses the movement of the lead-screw M, and returns the tool-carriage to the point of starting. When the carriage is carried back so that projection m' strikes the projection 1 on the rod m, arm n' is drawn back, and, through the 80 bevel-gearing o and o' and connections, shifts the sleeve H, and reverses the movement of the lead-screw M, so as to carry the carriage and tool forward in contact with the roller. At the moment of contact of the projection m' 85 with projection 1, the arm X also comes in contact with the lug 4, and, by means of its connections, through the rock-shaft x' and rod x³ and spring x, with the lever controlling the cutting-tool, forces the tool in position for cutting against the face of the roller. Now, while the lead-screw is turning to the right and drawing the carriage A' toward the shaft L, its bevel-wheel N, engaging with bevel-wheel N', will cause its shaft to turn cog-wheel 90 d, and, through idler d' and the cog-wheel d'', to turn the shaft U, causing its worm to move the segment T in a direction from the cog-wheel d''. The shaft of the worm w is mounted in bearings t t on the flange of segment T, 95 as before stated, and the threads of worm w engage with the teeth of a worm-wheel V, secured to the hollow shaft Z. This shaft Z carries a bell-chuck, in which the shaft of the roll to be grooved is secured, and when the 100 segment T is moved from the cog d'' the worm w will push up the teeth of the cog-wheel V, and cause it to turn the shaft Z slowly, and of course as the shaft Z turns it will turn the roll that is being grooved, so that the cut made 105 by the tool will be spiral. When the direction of the rotation of lead-screw M is changed, and while the carriage A' is being returned, the bevel-wheel N, operating through the chain of gearing before described, will 110 cause the segment T and worm w to turn the hollow shaft Z and roll back into position for a fresh cut, and in the meantime the worm O' on shaft M has operated the wheel O, that carries the cam P, and has caused this cam P to 115 depress the arm q of the lever Q, and has caused the forked arm R of shaft s to throw the sleeve Z outward, and with it the rod p, and when this occurs the rings a on shaft p 120 will turn the small wheel a', the shaft of which carries a segment-wheel, b', and this wheel, acting upon segment b, will cause its ratchet c' to jig the ratchet-wheel c, which in turn will partly revolve the worm w. The pawl c' turns

the ratchet-wheel *c* intermittently, and the jiggling takes place just as the carriage *A'* has been returned for a fresh cut. The worm *w*, when operated by the jiggling of ratchet-wheel *c*, very slightly turns the cog-wheel *V*, and this turns the shaft *Z* and the roller, to give the proper feed.

I have two means of regulating the amount of feed to determine the number of grooves on a roll. In the first place, by means of the screw *q*, I may elevate the weighted end of the lever *Q*, so that its arm *q* will be held so low as to be cleared by cam *P* when carried down by wheel *O*. Then the machine will not feed at all, and from this point the lever *Q* may be so adjusted by screw *q* that the cam may strike as soon as it begins to move, and carry the sleeve *Z* from one end to the other of the slots in shaft *Z'*. This will cause the rings *aa* on rod *p* to revolve the wheel *a'* far enough to take up the entire range of adjustment; but even this may not be sufficient, and therefore I may replace the ratchet *c* by one carrying a greater or less number of teeth. The shaft of cog-wheel *d* has its bearings in a slotted arm, *N*, the hub of which slips over the shaft of bevel-wheel *N'*, and is bolted to its bearings, so as to be adjustable about the center of motion of cog-wheel *d*. By this arrangement I am enabled to replace the pinion *d* by one of greater or less diameter, and thus regulate the speed of the shaft *U*.

When I desire to grind off the surface of an old roll preparatory to regrooving it, I move the brackets *E E* nearer to the shaft *L*, and, placing the shaft of the roll in its bearings, I secure it by a bell-chuck to the shaft of a wheel, *D'*, that has its bearings in a bracket, *F*. I then remove the plate *G* of carriage *A'*, that carries the tool-holder, and replace it by a plate carrying brackets, in which is journaled a grinding-wheel, *G'*, and on one end of the shaft of this wheel *G'*, I key a pulley, and belt it to any suitable source of power. I then shift the miter *I'* into gear with the bevel *I*, and when the shaft *L* turns it will reciprocate the carriage *A'*, as before stated, and at the same time this shaft, through its worm, will revolve the wheel *D'* and its shaft, which in turn will revolve the roller, so as to present its whole surface to the grinding-wheel. Of course while the grinding mechanism is in

operation the lead-wheel must be disconnected from the grooving feed mechanism, and this I do by removing cog-wheel *d* and worm-wheel *O*. 55

What I claim as my invention, and desire to secure by Letters Patent, is—

1. The combination, with a frame provided with stops 3 4, of a movable tool-holder actuated by a lead-screw, and provided with a rock-shaft, *x'*, with crank ends, slotted connecting-rod *x*, and spring *x*, substantially as and for the purpose set forth. 60

2. The device for reversing the lead-screw, consisting of a rod, *M*, rock-shaft *n*, and shaft 65 *r'*, geared thereto, and having a tubular arm, *r'*, in combination with a spring-rod, bell-crank, lever, a clutch, and sleeves carrying bevel-wheels, as set forth.

3. The combination, with a movable tool-holder provided with the projection *m'*, of the rod *m*, provided with the projections 1 and 2, rock-shaft *n*, with arm *n'*, shaft *r'*, clutch *H*, and connecting-gearing, substantially as and for the purposes set forth. 70

4. The combination of lead-screw *M*, carrying a worm, *O'*, a wheel carrying cam *P*, a rocking lever, *Q*, sleeve *Z'*, a rod, *p*, wheel *a'*, segments *b'* and *b*, a ratchet-wheel, *c*, with a ratchet, *c'*, worm *w*, wheel *V*, and the hollow 80 shaft *Z*, as set forth. 75

5. The combination of the lever *Q*, having arms *q* and *q'*, weight *q*, and adjusting-screw *q*, and forked arm *R*, with rod *p*, as set forth.

6. The shaft *L*, with loose bevel-wheel *I'* and 85 sleeve *H*, in combination with the bevel-wheel *I* and lead-screw *M*, substantially as and for the purpose set forth.

7. The shaft *L*, with sleeve *H*, and sleeve *L'*, with miter-wheel *K'*, in combination with the 90 miter-wheel *K* and lead-screw *M*, substantially as and for the purpose set forth.

8. Shaft *L*, sleeve *H*, and sleeve *L'*, with bevel-wheel *I'*, in combination with the bevel-wheel *I* and lead-screw *M*, substantially as and 95 for the purpose set forth.

In testimony that I claim the foregoing I have hereunto set my hand this 21st day of November, 1881.

ERNEST REIN.
